Primary Examiner — Mehri F Bajoul*(74) Attorney, Agent, or Firm* — Lee & Hayes, P.C.(57) **CLAIM**

The ornamental design for a game controller, as shown and described.

DESCRIPTION

FIG. 1 is a back perspective view of a game controller; FIG. 2 is a front perspective view thereof; FIG. 3 is a front view thereof; FIG. 4 is a back view thereof; FIG. 5 is a left-side view thereof; FIG. 6 is a right-side view thereof; FIG. 7 is a top view thereof; and, FIG. 8 is a bottom view thereof. FIGS. 1-8 illustrate a right-hand game controller; it is understood that the views of a left-hand game controller are mirror images of the views shown in the FIGS. 1-8.

The broken lines depict portions of the game controller that form no part of the claimed design.
